(57) CLAIM

We claim the ornamental design for the barbecue grill toy, as shown and described.

DESCRIPTION

FIG. 1 is a front perspective view of a barbecue grill toy showing our new design.

FIG. 2 is another front perspective side view thereof.

FIG. 3 is a front elevation view thereof.

FIG. 4 is a left side view thereof.

FIG. 5 is a rear view thereof.

FIG. 6 is a right side view thereof.

FIG. 7 is a bottom view thereof.

FIG. 8 is a top view thereof.

FIG. 9 is a perspective view thereof in an open configuration; and,

FIG. 10 is another perspective view thereof in an open configuration.

The broken lines in the figures form no part of the claimed design.

1 Claim, 10 Drawing Sheets
